ATTORNEYS.

UNITED STATES PATENT OFFICE.

DAVID G. YOUNG, OF COLUMBIA, NEW YORK.

CURD-CUTTER.

SPECIFICATION forming part of Letters Patent No. 271,969, dated February 6, 1883.

Application filed September 9, 1882. (No model.)

To all whom it may concern:

Be it known that I, DAVID G. YOUNG, a citizen of the United States, residing at Columbia, in the county of Herkimer and State of New York, have invented certain new and useful Improvements in Curd-Cutters, of which the following is a specification, reference being had therein to the accompanying drawings.

My invention relates to an improvement 10 in dairy-knives or curd-cutters for the manufacture of cheese; and it consists in a series of double-edged blades secured to a metallic or other head-plate by screws, bolts, or rivets, and having a twist near the head, so that the 15 plane of the cutting portion of the blade shall be at right angles with that of the head-plate and the knives at equal distances apart; also, in combining with them one or more stays or cross-blades in two or more parts, with slots 20 in their outer edges, the purpose of which will be presently explained; also, in certain other details of construction hereinafter more specifically described and shown.

The object of my invention is to construct a 25 dairy-knife or curd-cutter that shall be lighter and simpler in construction than those heretofore used, also one in which a wider cross-blade than heretofore is provided and the liability of displacement or slipping of the blades 30 upon the stay or cross-blade prevented, and the blades rigidly braced apart and securely held in position, thus securing absolute uniformity in their operation.

In the drawings, Figure 1 is a front view of my 35 curd-cutter. Fig. 2 is a sectional side elevation through the line *y*-*y*. Fig. 3 is a vertical cross-section through the line *x*-*x*, showing the cross-blade or stay. Fig. 4 is a detail view showing section of the stay or cross-blade in position. Fig. 5 is a section of one of the parts of 40 the cross-blade, showing the slots in its edge. Fig. 6 is a detail view showing a modification in the form of the cross-blade. Fig. 7 is also a detail view showing a modification in the 45 form of the cross-blade. Fig. 8 is a section of one of the blades, showing the slot or opening in the blade through which the stay or cross-blade is inserted.

In dairy-knives as heretofore constructed 50 various forms of head have been used, all of which are more or less cumbersome, as it has

been found difficult to secure the necessary strength and rigidity without the use of considerable material, as in all cases the blade has been inserted at right angles to the line of 55 the head, requiring either a solid head or a plate attached to one or both edges, which construction is open to many objections. The stay or cross-blade has also usually been narrow and confined to place and the knives prevented from slipping by swaging or the employment of solder at the point of contact, both of which means are found ineffectual. These objections are entirely obviated by my 60 construction, which is as follows:

I provide a single plate, A, for the head, which may be composed either of metal or of wood. The blades of which my knife are composed are then given a half-twist at the end 65 near the head, as shown at *a*, Fig. 1, so that a flat surface of their entire width is presented for contact with the head, and they are secured thereto by screws or bolts, so that they may be readily removed, or they may be firmly riveted thereto. By this twist the plane of the 70 cutting portion of the blades is made to assume a position at right angles with that of the head and the cutting-edges ranged side by side at suitable distances apart. These distances are uniformly and securely maintained by 75 means of the stays or cross-blades C, which are constructed in two or more parts, *b* *c* *d*, as shown in Figs. 4, 6 and 7.

b and *d* represent the parts of which the 80 cross-blade proper is composed, which are similar in construction, and when joined or united at their backs they form a continuous blade 85 slightly less in width than the others and corresponding in length to the width of the knife. They are sharpened on their outer edge and provided with slots *e*, as shown in Fig. 5, corresponding in number to the blades B and in 90 width to the thickness of the blades.

A horizontal slot, H, is formed through the 95 long blades B, which is in length one-half the width of the blade C when in place, but in width equal to double its thickness. The two sections, *b* *d*, are then inserted through this slot and forced into position, so that their backs 100 will be in contact and their edges outward, and the blades B will fill the space formed by the slots *e*. The key-piece *c* is then inserted be-

neath and riveted or soldered at its outer ends, *i*, and serves to completely fill the space *H* and confine the parts of the cross-blade or stay *C* in its place, as shown in Fig. 4, and the openings or slots *e* occupied by the blades *B* serve to firmly brace them in position and effectually prevent any lateral movement. By this construction a wider cross-blade may be employed than formerly without weakening or reducing the strength of the blades *B*, as would be the case were the horizontal slot equal in length to the width of the cross-blade. I do not, however, confine my construction to placing the key *c* beneath or alongside of the parts composing the cross-blade, as above shown; but it may be placed in rear of one of the parts, as shown in Fig. 6, in which case its outer edge may be sharpened; or it may be placed between them, as shown in Fig. 7.

20 When either of these constructions are employed the horizontal slot *H* in the blades *B* need only correspond in width to one thickness of the blade, thereby reducing the resistance of the stay or cross-blade to the minimum in operating the device.

Having thus described my invention, what I claim, and desire to secure by Letters Patent, is—

1. As a new article of manufacture, a dairy-knife having a series of separate double-edged parallel blades, twisted at one end and secured to a head-plate in such manner that the plane of the cutting portion of each blade shall be at right angles with the head, substantially as and for the purpose described.

30 2. The combination, in a curd-cutter, of

separate parallel double-edged blades secured to a head-plate, with a sectional cross-blade having slots in one or both of its outer edges, said cross-blade passing through slots in the parallel blades, said slots being of less length than the width of the cross-blades and of sufficient width to permit the insertion of the cross-blade and locking device, substantially as and for the purpose described.

40 3. A dairy-knife consisting of a head-plate and handle, a series of separate double-edged blades, made as described, and secured to the head-plate, and one or more cross-blades slotted in their outer edges and entering slots in the cutting-knives, and secured thereto by suitable keys, substantially as and for the purpose set forth.

45 4. The combination, in a dairy-knife or curd-cutter, of the head-plate *A*, the series of double-edged parallel blades *B*, provided with the twists *a* near their head, whereby a flat surface is brought into contact with and secured to the head-plate, and the sectional stay or cross-blade *C*, having slots *e*, whereby a wide cross-blade is provided without weakening the blades *B*, and the parallel blades and cross-blades are firmly and securely braced and locked in position by a suitable locking device, substantially as and for the purpose set forth.

50 55 In testimony whereof I affix my signature in presence of two witnesses.

DAVID G. YOUNG.
